COMBINATION FOCUSING TELESCOPE AND RE- CORDING CAMERA OR SIMILAR ARTICLE

Alexander J. Rassey, 3310 Bently Ave.,
Los Angeles, Calif.

Filed June 28, 1960, Ser. No. 61,140

Term of patent 14 years

(Cl. D57—1)

FIG. 1

FIG. 2

Fig. 3

FIGURE 1 is a side elevation view of a combination focusing telescope and recording camera or similar article, showing my new design.

FIGURE 2 is an angled top view thereof, taken along line 2—2 in FIGURE 1.

FIGURE 3 is a perspective view thereof.

The dominant features of my design are shown in solid lines.

I claim:

The ornamental design for a combination focusing telescope and recording camera or similar article, substantially as shown and described.
